(57) **CLAIM**

The ornamental design for exercise equipment carrying apparatus, as shown and described.

DESCRIPTION

FIG. 1 is a perspective view of an exercise equipment carrying apparatus; shown in an "in use" configuration;

FIG. 2 is a perspective view shown in an alternate position;

FIG. 3 is a front elevational view of FIG. 2;

FIG. 4 is a rear elevational view of FIG. 2;

FIG. 5 is a left side elevational view of FIG. 2;

FIG. 6 is a right side elevational view of FIG. 2;

FIG. 7 is a top plan view of FIG. 2;

FIG. 8 is a bottom plan view of FIG. 2;

FIG. 9 is a perspective view of FIG. 1; and,

FIG. 10 is another perspective view being shown in an "in use" configuration.

The broken line showing is included for the purpose of illustrating and forms no part of the claimed design.
